UNITED STATES PATENT OFFICE.

JAMES H. THORP, OF BROOKLYN, NEW YORK.

DESIGN FOR GIMP.

Specification forming part of Design No. **11,566**, dated December 30, 1879; application filed July 7, 1879.
[Term of patent 7 years.]

To all whom it may concern:

Be it known that I, JAMES H. THORP, of Brooklyn, in the county of Kings and State of New York, have invented a new and original Design for Gimp, of which the following is a specification.

The photographic illustration represents a face view of my new design for gimp.

This invention relates to a new ornamentation for gimp and analogous fabrics.

The body of the gimp contains a series of diamond or lozenge shaped figures, *a a*, placed in a row and at a short distance one from the other. Each of the figures *a* is composed of short parallel bars, forming a zigzag outline, as shown. Within each of the figures *a* is a small cross, *b*, formed of two crossed bars. At one side of the figures *a a* is a stripe, *d*, which is parallel to the bars or stripes that form the figures *a*.

I claim as my invention—

1. The design for a gimp, consisting of the figures *a a*, which are composed of parallel bars, and form a zigzag outline, substantially as shown.
2. The design for a gimp, consisting of the figures *a* and inner crosses, *b*, substantially as shown.
3. The design for a gimp, consisting of the figures *a* and stripe *d*, substantially as shown.
4. The design for a gimp, consisting of the figures *a*, crosses *b*, and stripe *d*, substantially as shown.

JAMES H. THORP.
